CHARGING APPARATUS FOR BOILER-FURNACES.

No. 832,629.

Specification of Letters Patent.

Patented Oct. 9, 1906.

Application filed September 1, 1905. Serial No. 276,680.

To all whom it may concern:

Be it known that we, FRIEDRICH WILHELM SEYBOTH and ERNST KARL ALEXANDER BAUMANN, subjects of the German Emperor, and residents of Zwickau, Saxony, Germany, have invented a certain new and useful Improvement in Charging Apparatus for Boiler-Furnaces, of which the following is a specification.

10 This invention relates to charging apparatus for boiler-furnaces; and the objects of our improvement are to provide novel and efficient means for crushing fuel, feeding the fuel, and controlling and regulating the distribution of the fuel.

15 Prior to our improvements charging or stoking devices for boiler-furnaces have been provided wherein the quantity of coal to be distributed uniformly over the grate corresponding to the consumption of steam is fed to the blades of a throwing paddle-wheel from a breaking-roll, the rotation of which roll is controlled from a steam-pressure regulator. These charging devices suffer from 20 the disadvantage that in the usual steam-pressure regulators directly operating the breaking-rollers the regulation is not sensitive, but requires considerable fluctuations. They also have the disadvantage that with 25

30 fuel of varying hardness in consequence of the various sizes of material broken up by the breaking-roll and thrown by the wheel onto the grate the distribution even with uniform consumption of steam is not uniform, and 35 further fluctuations in the steam-pressure result. In consequence the purpose of an automatically-regulated charging device to keep the steam-pressure as near constant as possible independent of the steam consumption 40 is not served.

The subject of the present invention is an automatically-regulated charging device or stoker which avoids these drawbacks, and the present improvements utilize resilient or 45 yielding charging devices which are controlled from a steam-pressure regulator. A breaking-roll is employed which cooperates with a resiliently-mounted breaking-plate, the driving device of which roll is moved 50 from a steam-pressure regulator in such a way that with the slightest variations of steam-pressure, which at the most amount to

one per cent. of the normal steam-pressure, the extent of rotation of the breaking-roll is changed. This breaking-roll guides the material, broken into uniform size, to a wheel having elastic blades, which effect the uniform distribution of the coal on the grate. 55

The subject-matter of the invention is shown in Figures 1 to 11. Fig. 1 shows a cross-section of the automatic charging device; Fig. 2, a side view of the same; Fig. 3, a vertical longitudinal section through the charging device connected with the automatic steam-pressure regulator. Fig. 4 is a detail view, partly sectional, showing the manner of assembling the parts of the distributing-wheel of Fig. 1. Figs. 5 and 6 are respectively cross-sectional and longitudinal views of another construction of distributing-wheel. Figs. 7 and 8 are longitudinal and side views of a third construction of distributing-wheel. Fig. 9 is a detail vertical sectional view of a modified form of device for regulating the fuel-crushing device. Fig. 10 is a side view of the ratchet-wheel thereof and pawl-shield; and Fig. 11 is an end view showing the relations of ratchet, pawl-shield, and pawl. 70 75 80

The apparatus in the form illustrated consists of the following parts:

The fuel-breaking mechanism.—This includes a roll 1, which breaks the coal thrown into the hopper to a uniform size. This breaking-roll 1 works near an elastically-mounted or yielding breaking-plate 2, which breaking-plate 2 oscillates upon the trunnions 3 and is held in its normal position by an arm 4 and coil-spring 5, this resilient arrangement of the breaking-plate enabling 85 said plate to yield when stone or harder coals pass through. The breaking-plate 2 may also, if desired, be opened as a door for a manual feeding-space when the arm 4 is pressed upwardly against the pressure of the spring 5, 90 so as to enable the plate 2 to turn on the trunnions 3.

The throwing device.—This effects the delivery of the previously-broken coal uniformly on the grate and consists of one or 100 more wheels 6, which throw the charge into the furnace-space with varying velocity. While the different velocity was heretofore obtained by blades of different length or by

special driving mechanism, such as elliptical wheels, in the present invention the elastic paddle-blades 7 are bent to a different degree by a strip 8, so that after brushing over this strip in consequence of their bending the blades spring forward and throw the coal onto the grate. The several different paddle-blades may therefore differ very little in length, as a few millimeters suffice to give 10 the required different degrees of bending on brushing over the strip 8. By means of the arrangement of the elastic blades as above mentioned the further advantage is obtained that a breakage of the blades in consequence 15 of the jamming of the coal is not possible.

The blades can be made of steel wire or sheet-steel, (metal-wire or sheet metal,) according to Figs. 1 and 2 or Figs. 5 and 6. These blades can be fastened to the axle by 20 means of blocks or bars 9, which are held together, Fig. 4, by bosses 10, the conical recesses of which engage the reduced ends of the blocks or bars 9, or the wire or sheets 15 may be gripped, Figs. 7 and 8, in special 25 holders 16 and secured to the axle 17. One or more of the blades can be set inclined to the axle, (see Fig. 7,) so that the fuel is not only thrown directly onto the center of the grate, but also against the sides. Instead of 30 wires or thin sheets the blades may, as shown in Figs. 5 and 6, be made of two or more resilient plates 11, with throwing-strip 12, said plates being bolted onto the prismatic bushes 13, mounted on the wheel-shaft 14.

35 The covers 23 of the casing, Figs. 2 and 3, have non-concentric perforations for mounting the shaft 14. Hence by turning the covers the shaft can be brought higher or lower—i. e., nearer or farther away from the strip 8—40 so that the bending of the blades to the required amount and corresponding to the wear of the strip can be controlled.

The mechanism for driving the charging devices with the steam-pressure regulator.

45 The wheel-shaft 14 is driven by means of belt-pulleys or toothed wheels and may drive the breaking-roll shaft through a counter-shaft. In the present case a crank 26, Fig. 3, is keyed to the wheel-shaft, the pin of 50 which carries a roller 24. This roller is moved in a slotted vibrating lever 25, pivoted to the breaking-roller shaft, on which lever a pawl 21 (see also Fig. 2) is secured rotatably on the pivot 20, which pawl engages a ratchet-wheel 22, keyed on the breaking- 55 roller shaft. Hence the breaking-roller is rotated through a small angle only for a complete rotation of the wheel-shaft. The extent of this angle determines the quantity of 60 fuel broken and fed during one rotation of the wheel 14, so that by regulation of this angle the supply of fuel can be regulated with the slightest variations in steam-pressure. With this object the pawl is provided with a 65 tongue 19, which is controlled to a certain

extent by a conical roller 18. The horizontal position of the conical roller 18 with relation to the tongue 19 determines the time when the pawl during the forward movement of the vibrating lever is disengaged 70 from roller 18 and falls into engagement with the ratchet connected with breaking-roll 1. The roller 18 is preferably adjustable, by hand or otherwise, to control the extent of movement of the breaking-roll 1, and the nearer the roller is to the outer side of the hopper the longer will be the engagement of said roller with the tongue 19 and the shorter the movement of the breaking-roll 1. In the present case the arrangement is such that 80 the position of the conical roller 18 is adjusted automatically and by a steam-pressure regulator. The steam-pressure regulator consists of a cylinder 27, Fig. 3, in which a piston 29 on one side is moved by spiral 85 spring 28 (or also an air-cushion) and on the other side by steam-pressure. To the piston 29 is pivotally connected a rod 30, which moves the bell-crank 31 round the pivot 32. The bell-crank 31 moves the rod 33, on 90 which the conical roller is keyed, and which passes through bushes 34 and through a tube passing across the hopper. The cylinder 27 is connected, through the tube 39, to the interior of the boiler. For the purpose of more 95 easily packing the regulator-piston there is placed directly under the piston an oil-cushion, which serves for lubricating the cylinder. To replenish the same, the cocks 40 and 41 are shut and the cock 42 opened. 100 Then the oil passes from the funnel 43 into the short pipe 44, from which it flows to the space beneath the piston 29 on opening the cocks 40 41 and closing of cock 42. Simultaneously with the regulation of the quantity 105 of fuel the regulation of the air-supply can be effected, as shown, by way of example, in Fig. 3, by permitting the bell-crank 31, by means of rod 35, crank 36, and shaft 37, to adjust the flap 38. In Figs. 9 to 11 is shown 110 another arrangement of regulator. In this case the movement of the pawl 21 is controlled by a regulating pawl-shield 45, arranged to move between pawl 21 and ratchet-wheel 22, which pawl-shield 45 is moved by 115 a rod 46 (corresponding to rod 30, hereinbefore mentioned) from the regulator, so that, according to the position of the shield, the engagement of the pawl 21 in the ratchet-wheel 22 takes place earlier or later. The 120 shield is mounted for oscillation upon the axis of the ratchet 22, which is positively connected with the breaking-roll 1, and the arrangement of pawl 21 and rocking lever 25 is the same as hereinbefore described. 125

Having now described our invention, what we claim, and desire to secure by Letters Patent of the United States, is—

1. In a charging apparatus for furnaces, a fuel-breaking roll, a fuel-distributing wheel 130

below said roll, a charging-door pivoted to permit the escape from the apparatus of foreign bodies, and said door carrying a crushing-plate coöperating with the roll to crush the fuel and serving as a guide to direct the crushed fuel to the ditributing - wheel, a shaft and connections for operating said roll, and a steam-pressure regulator for varying the movement of said operating connections.

10 2. In charging apparatus for furnaces, a yielding fuel-breaking means comprising a yielding crushing-plate and a roll, a fuel-distributing wheel having resilent paddles for feeding fuel delivered from said roll, a pawl having a tongue and a ratchet engaged by said pawl and driving said roll, connections for operating said pawl as desired, a steam-pressure regulator, and a conical roller adjustably movable by said regulator and bearing upon the pawl-tongue aforesaid.

15

20

3. In a charging apparatus for furnaces, a yielding fuel-breaking means comprising a yielding crushing-plate and a roll, a fuel-distributing wheel for feeding fuel delivered from said roll, a pawl and a ratchet engaged by said pawl and driving said roll, connections for operating said pawl as desired, a steam-pressure regulator and means adjustably movable by said regulator, for regulating the duration of engagement of the pawl with the ratchet-wheel.

In testimony whereof we have signed our names to this specification in the presence of two subscribing witnesses.
